UNITED STATES PATENT OFFICE.

EMILE FERDINAND ADELIN CHARLES LEPERRE, OF ANTWERP, BELGIUM.

MACHINE FOR CUTTING DIAMONDS.

Application filed August 15, 1921. Serial No. 492,496.

To all whom it may concern:

Be it known that I, EMILE FERDINAND ADELIN CHARLES LEPERRE, a subject of the King of the Belgians, residing at 46 Rue du 5 Champ, Berchem, Antwerp, Belgium, have invented new and useful Improvements Relating to Machines for Cutting Diamonds, of which the following is a specification.

This invention relates to cutting machines 10 for precious stones and has for its object to provide an improved device for advancing the dop carrier electrically with hand control and for automatically withdrawing the dop carrier after a predetermined period of 15 engagement with the grinding tool.

According to the invention a grinding machine for precious stones includes a dop carrier mounted upon a solenoid casing 20 movable through mechanical connections actuated by its core to advance the dop towards the grinding tool, a circuit breaking device adjustable to operate after the dop has been advanced to a predetermined point serving to de-energize the solenoid and allow 25 the dop to be withdrawn automatically.

In the drawing is illustrated by way of example a form of construction of the subject of the invention.

Figure 1 shows a vertical longitudinal 30 section through a part of a grinding machine constructed according to this invention.

Figure 2 is an end view and section of the solenoid and associated parts.

35 Figure 3 is a diagram of the electric circuit and.

Figure 4 shows a plan of the contact bridge of the circuit in the open position.

The stone supporting apparatus or dop 1 40 is provided at its base with a shortened conical extension 2 which fits into a corresponding recess in a hollow cylinder 3 enclosing a solenoid 4 of which the core 5 carries at its inner end two levers 6. The 45 free ends of the levers 6 are provided with rollers 7 which bear upon an oscillating lever 8. The fulcrums of the levers 6 are formed by rollers 7' disposed within the interior of the hollow cylinder 3 and bearing against 50 the core 5. The oscillating lever 8 is adjustable in height and for this purpose is carried by a lever 9 which is mounted on a pivot 11 in the holder 10. The adjustment is effected by means of a screw 12 terminating 55 in a ball 13 above which engages a forked spring 14 secured to the lever 9 by a screw

15. In order to draw the hollow cylinder 3 backwardly when a current no longer flows through the winding of the solenoid it is connected to the holder 10 by a spiral 60 spring 16.

When a current passes through the winding of the solenoid 4, the core 5 is attracted. The levers 6 act by means of their supporting points (rollers 7) upon the oscillating 65 lever 8 and by their bearing points (rollers 7') against the underside of the cylinder so that the whole core 5, cylinder 3 with coil 4 and dop 1 are raised and the stone to be operated upon is brought into contact with 70 the grinding tool.

When the current is interrupted the core 5 is no longer attracted and the solenoid and associated parts are pulled downwards 75 by the action of the spring 16.

To the cylinder 3 is connected the push-slider 17 of a dial indicator 19 of a comparator of which the pointer 18 operated by the slider 17, indicates the movement of the parts 1, 3, 4 and 5 together. 80

The comparator is of the type generally known in industry.

The fore part of the solenoid 4 is connected with the mass of the machine; the end of that solenoid gets to the push-slider 85 17 and influences thus the body of the comparator and thence the pointer 18.

The pointer 18 is provided with a contact 20 and the dial plate with a contact 21 at the zero-point. The dial plate and the 90 pointer form a switch which breaks the circuit when the contacts 20 and 21 come into contact. The dial plate is adjustable, i. e. the zero point may be brought into a suitable position. 95

In series with the electro-magnet 4 is an electro-magnet 22 of which the winding is considerably shorter than that of the magnet 4 and is for example 1/100 thereof so that the attractive pull of the electro-magnet 100 22 is very weak and does not create any sparks at the switch 20, 21.

The mass of the comparator is insulated from the cylinder 3 and connected with one of the ends of the solenoid 22. The contact 105 bridge 21 being placed on the isolating-matter dial 19 is thus insulated from the mass of the comparator and united to the second extremity of the solenoid 22 and at the same time to the contact point 23. 110

When the core of the electro-magnet 22 is magnetized it attracts the iron plate 24

in such a manner that a bridge 24' provided thereon connects the two contact points 23 and 23'. When the magnetization ceases the bridge is raised under the action 5 of a spring 25.

In order to prevent any jerk of the diamond against the grinding tool when the solenoid 4 is energized, the core 5 of the latter is connected by a cord 28 to a hand 10 lever 26, supported by a spring 27, which keeps the cord 28 taut, and prevents the lever 26 from falling out of convenient reach of the operator. The hand lever 26 enables the operator to control the feed of the dop 15 towards the tool.

The method of operation of the machine is as follows:

By turning the dial plate of the indicator the zero point thereof is brought to a distance away from the contact point 20 of the pointer corresponding to the thickness to be ground off the stone. Then, whilst holding the hand lever 26, the circuit is closed by depressing the bridge 24' which 25 connects together the two contacts 23, 23'. The current passes through the two electromagnets arranged in series and energizes these so that the plate 24 with the bridge 24' attracted thereto remains in its lowered position. Whilst the core 5 is being attracted, the lever 26 is gradually released until the stone comes into contact with the grinding tool. As the grinding operation 30 proceeds, the pointer 18 indicates the feed and when the pointer comes into contact with the contact point 21 at the zero point of the dial plate the electro-magnet 22 is short circuited. The contact bridge 24' will 35 then no longer be attracted and rises under the action of the spring 25 breaking the circuit by leaving the contacts 23, 23'. As the core 5 is now no longer attracted the cylinder 3 with the dop 1 is pulled away 40 from the grinding tool by the spring 16.

45 I claim:—

1. A machine for cutting precious stones comprising a dop carrier, a solenoid core, an energizing coil surrounding said core, a casing surrounding said coil and supporting 50 said dop carrier, a pair of levers pivoted to said core, means for supporting the free ends of said levers, rollers on said coil casing bearing on said levers, a feed indicating device, means operated by said device for breaking the solenoid circuit and a spring for withdrawing said casing and dop carrier.

55 2. A machine for cutting precious stones comprising a dop carrier, a solenoid core,

a coil casing surrounding said core, means 60 operated by movement of said core for advancing said casing and dop carrier, a feed indicating device, a fixed contact on said device, an electro-magnet in series with the solenoid coil, a bridge in the solenoid circuit controlled by said electro-magnet and a spring for withdrawing said casing and dop carrier.

3. A machine for cutting precious stones comprising a dop carrier, a solenoid core, 70 an energizing coil surrounding said core, a casing surrounding said coil and supporting said dop carrier, a pair of levers pivoted to said core, rollers on the free ends of said levers, an oscillating lever supporting said rollers, rollers on said coil casing bearing on said levers a feed indicating device, a fixed contact on said device, a moving contact on said device, an electro-magnet in series with the solenoid coil, a bridge 80 in the solenoid circuit controlled by said electro-magnet and a spring for withdrawing said casing and dop carrier.

4. A machine for cutting precious stones comprising a dop carrier, a solenoid core, 85 an energizing coil surrounding said core, a casing surrounding said coil and supporting said dop carrier, a pair of levers pivoted to said core, rollers on the free ends of said levers, an oscillating lever supporting said rollers, rollers on said coil casing bearing on said levers a feed indicating device, a fixed contact on said device, a moving contact on said device, an electro-magnet in series with the solenoid coil, a bridge in 95 the solenoid circuit controlled by said electromagnet, a spring tending to retain said bridge in open position and a spring for withdrawing said casing and dop carrier.

5. A machine for cutting precious stones 100 comprising a dop carrier, a solenoid core, an energizing coil surrounding said core, a casing surrounding said coil and supporting said dop carrier, a pair of levers pivoted to said core, rollers on the free ends 105 of said levers, an oscillating lever supporting said rollers, rollers on said coil casing bearing on said levers, a feed indicating device, a fixed contact on said device, a moving contact on said device, an electro-magnet in series with the solenoid coil, a bridge in 110 the solenoid circuit controlled by said electro-magnet, a spring tending to retain said bridge in open position, a pivoted hand lever, a connection between said hand lever and the solenoid core and a spring for withdrawing said casing and dop carrier.

EMILE FERDINAND ADELIN CHARLES LEPPERRE.
